UNITED STATES PATENT OFFICE.

CLARENCE CHESTER ROWE, OF SPRAY, NORTH CAROLINA.

CLOTH-TREATING MACHINE.

1,357,118.

Specification of Letters Patent. Patented Oct. 26, 1920.

Application filed May 8, 1920. Serial No. 379,880.

To all whom it may concern:

Be it known that I, CLARENCE C. ROWE, a citizen of the United States, residing at Spray, in the county of Rockingham and State of North Carolina, have invented new and useful Improvements in Cloth-Treating Machines, of which the following is a specification.

This invention relates to machines for treating fabric, and has particular reference to that type of machine wherein the fabric is drawn by feed rolls through a tank or pit subjecting the fabric to a chemical bath. In machines of this character, the fabric coming from the washer runs over the reel into the tank or pit containing the chemical solution, and is drawn through and from the pit or tank by means of a pair of feed rolls. In order for the fabric to be properly treated within the tank or pit it is necessary to maintain a certain amount of slack in that part of the fabric positioned within the tank. It frequently happens however that the feed rolls gain on the reel from which the fabric is unwound, with the result that the slack in the fabric is soon taken up. When this takes place, the fabric does not pass through the tank or pit, but remains there a sufficient length of time to receive the necessary amount of chemicals, thereby making it necessary to throw this fabric into what is known as seconds. Again by pulling tight upon the fabric in the manner stated, it breaks the edges of the fabric.

It is therefore the purpose of this invention to provide means for maintaining the necessary slack for the fabric within the tank or pit, so that the fabric will receive the necessary amount of chemicals, the said means being actuated by the tensioning of the fabric to automatically stop the feed rolls.

More specifically stated, the invention provides a member supported for pivotal movement and projecting within the tank or pit and beneath which member, the fabric from the washer reel is drawn through the tank, the member being moved upon its pivot by tensioning of the fabric operating the clutch mechanism to automatically stop the feed rollers.

The nature and advantages of the invention will be better understood when the following detail description is read in connection with the accompanying drawings, the invention residing in the construction com-

bination and arrangement of parts as claimed.

In the drawings forming part of this application like numerals of reference indicate similar parts in the several views and wherein:

Figure 1 is a longitudinal sectional view through a tank or pit showing the invention associated therewith.

Fig. 2 is a top plan view.

Fig. 3 is a transverse sectional view taken on the line 3—3 of Fig. 1 looking in the direction of the feed rolls.

Fig. 4 is a similar view looking in the direction of the clutch controlling member forming the subject matter of the invention.

Referring to the drawings in detail, 10 indicates the tank or pit which contains a chemical solution for proper treatment of 15 the fabric 11, as the latter passes through the tank or pit. In machines of this character, the fabric in leaving the washer, not shown, is trained over a reel 12, and directed into the tank 10, being drawn through 20 the tank by means of the feed rolls 13 and 14 respectively. These rolls are driven in any suitable manner and controlled by means of a clutch mechanism including a 25 lever 15.

In accordance with my invention, I provide a shaft 16 which is journaled in spaced bearings 17 arranged upon the opposite sides of the tank or pit 10. Depending from this shaft is a member 18 of any suitable 30 construction and configuration, this member being positioned within the tank or pit 10, and spaced a slight distance from the bottom of the latter. Carried by the shaft 16 is an arm 19 to which is connected one 35 end of an operating cable 20, the latter being trained over guide pulleys 21 and having its opposite end suitably connected to the clutch control lever 15. In practice the 40 fabric 11, is trained over the reel 12 and 45 directed into the pit or tank 10, passing beneath the member 18, which serves to maintain the requisite amount of slack in the 50 fabric so that the latter will be properly treated by the chemicals contained therein.

The fabric 11 is drawn by the feed rolls 55 13 into the tank in the usual manner. However in order to avoid undue pull or strain upon the fabric 11, and to also prevent the feed rolls 13 from taking up the slack in 60 the fabrics, so that the proper amount of fabric will not pass through the tank or 65

pit or remain in the tank or pit the requisite amount of time to be properly treated, I connect the arm 19 with the control lever 15 of the clutch mechanism. Obviously, 5 should the feed rolls 13 exert a tension or pull upon the fabric 11, the latter contacts the member 18 moving the same upon its pivot or shaft 16. Consequently the arm 19 is shifted to exert a pull upon the cable 10 20, which in turn actuates the lever 15 to disengage the clutch mechanism to thereby automatically bring the feed rolls 13 and 14 to a stop.

While it is believed that from the foregoing description the nature and advantages of the invention will be readily apparent, I desire to have it understood that I do not limit myself to the details herein shown and described, and that such changes 20 may be resorted to when desired as fall within the scope of what is claimed.

Having thus described my invention what I claim as new is:—

1. In combination with a machine for 25 treating fabric, including a tank and clutch controlled feed rolls for drawing the fabric through the tank, of a pivotally mounted member positioned within the tank and be-

neath which the fabric passes through the tank, said member being moved upon its pivot 30 for tensioning of the fabric, and a cable connection between said member and clutch controlled lever of the feed roll for the purpose specified.

2. The combination with a machine for 35 treating fabric including a tank and feed rolls for drawing the fabric through the tank, of a member suspended within the tank for oscillatory movement and beneath which the fabric is arranged, said member being 40 operated by tensioning the fabric to automatically stop the feed rolls.

3. The combination with a machine for 45 treating fabric including a tank, and clutch controlled feed rolls for drawing the fabric through the tank, of a member suspended within the tank for oscillatory movement and beneath which the fabric is passed through the tank, said member being actuated by the retention of the fabric, and a 50 cable connection for automatically stopping the feed rolls as described.

In testimony whereof I affix my signature.

CLARENCE CHESTER ROWE.
